J. C. SWAN.

APPARATUS FOR EXCLUDING WATER FROM DRILLED WELLS FOR OIL.

APPLICATION FILED FEB. 10, 1919.

1,413,197.

Patented Apr. 18, 1922.

UNITED STATES PATENT OFFICE.

JOHN C. SWAN, OF MARIETTA, OHIO.

APPARATUS FOR EXCLUDING WATER FROM DRILLED WELLS FOR OIL.

1,413,197.

Specification of Letters Patent. Patented Apr. 18, 1922.

Application filed February 10, 1919. Serial No. 276,116.

To all whom it may concern:

Be it known that I, JOHN C. SWAN, a citizen of the United States, residing at Marietta, in the county of Washington and State 5 of Ohio, have invented certain new and useful Improvements in Apparatus for Excluding Water from Drilled Wells for Oil, of which the following is a specification.

In the usual methods of drilling wells for 10 oil, it is the custom when a water-bearing stratum is encountered and drilled through to insert into the bore, a casing consisting of a series of lengths of connected steel or iron pipes of suitable diameter, this casing extending 15 beneath the water-bearing stratum and thereby shutting off the water from the bore. As successive water-bearing strata are encountered, additional strings of casing are inserted. These successive strings extend one 20 inside the other from the surface to a location below the water and the need of them necessitates the starting of the bore with a sufficient diameter to permit the insertion of as many strings of casing as may be necessary. 25

Obviously, large quantities of steel and iron in the form of pipes are used, and the cost of transportation to the location where the hole is being bored and the cost of labor 30 for their installation is very large in addition to the purchase cost.

Further the drilling of an initially large hole is necessitated, which adds to the cost of the well.

35 In my companion application, Serial No. 253,082, filed September 7, 1918, now Patent No. 1,307,027, patented June 17, 1919, I have described a method of sealing up the successive water-bearing strata in the bore, 40 whereby the necessity for using successive strings of casing and the expense of drilling large holes are obviated.

According to this method, the porous, seamed, or stratified rock through which the 45 water enters the bore is preferably first heated, to such a degree that a fluid sealing compound forced into the bore will freely enter the pores or interstices of the water-containing stratum and will thereafter 50 seal or set into a mass sufficiently solid to prevent the further ingress of water into the bore. As such sealing compounds, I prefer to use materials which are liquid at temperatures above the natural temperature of 55 the water-bearing stratum, but which will be solid or semi-solid at that temperature.

Such materials are paraffin, resin, coal-tar, pitch, asphalt, etc., either alone or in suitable combination with each other or other materials which will give them the property 60 above referred to.

As described in such companion application, in carrying out the method where a compound is used which requires heat to make it liquid, I force into the well a suitable 65 heating medium such as hot water which may be heated under sufficient pressure to raise its temperature to a suitable degree above its boiling point at atmospheric pressure. The hot water is forced into the well 70 under sufficient pressure to overcome the hydrostatic head of the water in the porous stratum and forces its way into the porous mass thereby heating the same to such a degree that when the liquified sealing compound is introduced it will be able to permeate the water bearing strata to the desired extent to insure complete exclusion of the water from the bore of the well when the material is allowed to cool and set in place. 75

Different filling materials will require different temperatures for successful penetration of the porous rock, e. g. asphalt will require a considerably higher temperature than paraffin. 80

The present invention relates to the apparatus for carrying out the method described and one embodiment thereof is illustrated in the accompanying drawing, wherein the figure represents a section through a 90 drilled well showing the apparatus in place.

Referring to these drawings, 1 is the bore of the well, 2 is a string of steel or iron pipes extending downward into the bore. Surrounding the string 2 is a second string 3 95 whose lower length is, at its lower end, secured through suitable couplings 4 to the pipe 2. As shown, this connection is made by an ordinary form of screw pipe coupling, but it is preferred to weld this joint so that the lower portion of the pipe 3 is hermetically sealed to the interior piping 2. At its upper portion the pipe 3 is provided with a stuffing box 5 through which passes the pipe 2, and is also provided with a T-head to 100 which is connected the pipe 6 provided with an outwardly opening check valve 7, and a shut-off valve 8, this pipe leading, as indicated to any suitable form of vacuum pump. The purpose of this arrangement is to provide around the greater portion of the length 110 of the pipe 2 a heat-insulating chamber

whereby the loss of heat from the hot water and rock filling compound is prevented.

While I have described means for producing a substantial vacuum, this may be unnecessary at depths of less than 1000 feet, and the dead air space alone will probably afford sufficient heat insulation to maintain a workable temperature for both the hot water and the hot liquid filling material passed down the pipes 2.

It will be understood that the strings of pipe 2 and 3 are made up concurrently before being lowered into the well so that none of the water present in the well can find its way into the space between the string 2 and the string 3, and it is essential that water shall be excluded from this space.

The upper portion of the pipe 2 is provided with a coupling 40, to which is connected a valved pipe 20 leading to a suitable source of pressure fluid such as cold water, gas or air. Another valved pipe 42, is connected to any suitable means for supplying hot water, such as a steam boiler, not shown. 25 A removable screw-plug 16 is located at the top of the coupling to permit the insertion of the expandable pistons 17 and 18. These pistons are preferably cylinders of rubber formed with a central cavity.

30 Below the end of the heat-insulating casing 3 and around the pipe 2 and between that pipe and the wall of the bore is inserted an oil well packer 9 of the construction commonly used in oil wells, or of any special construction which the special circumstances of use may require. As shown the packer consists of a rubber tube 10 compressed between flange couplings 11 and 12, the coupling 11 being secured to the pipe 2, and the 40 coupling 12 resting upon pipe 13 which is in turn screwed on to the perforated pipe 14, this pipe constituting in effect a continuation of the pipe 2. As will be readily understood this packer provides a slip joint for the pipe 2 whereby the weight of the super- 45 incumbent strings of pipe will compress the rubber and force it inwardly and outwardly into a water tight engagement with the pipe 2 and the walls of the bore. The perforated 50 pipe 14 is provided at the bottom with a screw-cap closure 15.

The upper portion of the pipe 2 is machine-finished on the outside to provide a smooth surface whereby the pipe under the 55 expansion incident to heat may pass freely through the stuffing box 5 while maintaining a hermetically sealed joint.

In operation the vacuum pump withdraws the air from the space between the pipes 2 and 3 thereby forming an effective heat insulation around the pipe 2. Hot water which has been heated preferably under pressure so that it is at a suitable temperature, is passed downwardly from pipe 42 through the pipe 2 and out through the perforations

in the pipe 14 and thence into the chamber formed between the packer and the bottom of the well, and flows into the pores, crevices or seams of the water-bearing porous rock, forcing back the water contained therein, 70 and in its passage heating the body of the rock to a suitable temperature. This flow of hot water is continued for a time, which will depend upon the character of the rock, until the heating to the requisite temperature 75 has extended radially from the bore to a sufficient distance. The supply of hot water is then shut off, the plug 16 at the top of pipe 2 is removed and an expandible piston 17, preferably of rubber, is then inserted 80 into the pipe 2 and the charge of liquid filling compound is introduced. A second expandible piston 18 is then inserted over the charge of liquid filling compound and the plug 16 replaced. The pistons are then 85 forced down into the bore by a suitable pressure means, such as cold water or high pressure air or gas introduced through the pipe 20. Under the pressure thus exerted the lower piston will move to the bottom of 90 pipe 2 whereupon the charge of liquid filling compound will flow through the perforations and into the interstices, seams or crevices in the water bearing porous rock. This impregnation of the water bearing stratum 95 will proceed from the bore outwardly until the liquid filling material comes into contact with the rock material at a temperature low enough to cause it to congeal or freeze in place thereby completely sealing the orifices 100 through which water enters the seal and the balance of the filler is held under pressure for the necessary period of time to effect cooling to congelation.

This same operation is repeated as often 105 as water producing strata are penetrated by the bore. In the absence of caving walls the bore of the well may be of the same diameter from the surface of the ground to the finished depth of the well.

110 After the withdrawal of the strings of pipe 2 and 3 and the packing, the residual mass of filling material can be drilled up by the usual process of drilling.

It will be apparent therefore that my invention enables a perfectly and permanently dry well to be bored without the use of any casings for the purpose of excluding water, since the filling material when solidified forms a water-excluding barrier of sufficient 120 strength to withstand the hydrostatic pressure behind it.

Ordinarily water is encountered in sandstone which varies in texture from large crystalline formation to very fine grain. 125

It will be readily understood that the coarser grained structure will absorb larger quantities of the filling material and fill further back from the bore hole than the finer grain formation; and in the event of 130

large crevices being present, a larger quantity of filling material must be used to obtain the necessary penetration for successful water exclusion.

5 It will be noted that the string of tubing has secured to it, near its lower end and above the packer, the lower section or "joint" of the casing by a fluid-tight connection. The successive sections or joints of 10 the tubing and casing are secured together respectively before lowering into the well, the lowering of the combined tubing and casing into the well being effected by attachment of the elevators to the casing by 15 the common and well known method. I believe that I am the first to propose the concurrent lowering into a well of a combined string of tubing and casing having between them a fluid-tight space.

20 In this art, the term "tubing" is usually applied to the inner piping through which the oil flows from the well; while the term "casing" is applied to the piping surrounding the "tubing", and these terms are used 25 in the claims with these meanings.

I claim:

1. Apparatus for excluding water from wells, comprising a string of tubing open at its lower end to the water-bearing stratum of the well, means for introducing congealable, liquid filling-material through said tubing under pressure into the water-bearing stratum, a casing-jacket around the tubing, and means for producing a vacuum in 35 said jacket.

2. Apparatus for excluding water from wells, comprising a string of tubing open at its lower end to the water-bearing stratum of the well, means for introducing a heating medium and means for forcing congealable, liquid filling-material through said tubing

30

35

40

45 into the water-bearing stratum, and a vacuum heat-insulating jacket surrounding said tubing.

3. Apparatus for excluding water from wells, comprising a string of tubing open at its lower end to the water-bearing stratum 50 of the well, means for introducing a heating medium and means for forcing congealable, liquid filling-material through said tubing into the water-bearing stratum, a casing jacket around the tubing, and means for 55 producing a vacuum within said jacket.

4. Apparatus for excluding water from wells, comprising a string of tubing open at its lower end to the water-bearing stratum 60 of the well, means for introducing hot water into the tubing, means for forcing congealable, liquid-filling material through said tubing into the water-bearing stratum including a pair of pistons between which the charge of filling-material is carried through 65 said tubing and a source of fluid pressure, and heat-insulating means for said tubing.

5. Apparatus for excluding water from wells, comprising a string of tubing open at its lower end, a packer surrounding said 70 tubing near its lower end, and a fluid-tight casing-jacket surrounding said tubing above the packer.

6. Apparatus for excluding water from wells, comprising a string of tubing open at 75 its lower end, a packer surrounding said tubing near its lower end, a fluid-tight casing-jacket surrounding said tubing above the packer, and means for introducing congealable, liquid filling-material through said 80 tubing under pressure into the water-bearing stratum.

In testimony whereof, I affix my signature.

JOHN C. SWAN.
